UNITED STATES PATENT OFFICE.

FRED L. WEBSTER, OF DANVERS, MASSACHUSETTS.

MACHINE FOR PARING SQUASHES.

SPECIFICATION forming part of Letters Patent No. 404,452, dated June 4, 1889.

Application filed November 3, 1888. Serial No. 289,926. (No model.)

To all whom it may concern:

Be it known that I, FRED L. WEBSTER, of Danvers, in the county of Essex, State of Massachusetts, have invented a certain new and useful Improvement in Machines for Paring Squashes, &c., of which the following is a description sufficiently full, clear, and exact to enable any person skilled in the art or science to which said invention appertains to make and use the same, reference being had to the accompanying drawings, forming part of this specification, in which—

Figure 1 is a vertical transverse section of my improved squash-parer, some of the parts being shown in side elevation; Fig. 2, an elevation representing the machine in use; Fig. 3, an end elevation of the machine enlarged; Fig. 4, a top plan view of the same; Fig. 5, an enlarged perspective view of the knife detached, and Fig. 6 sectional views illustrating certain details of construction.

Like letters and figures of reference indicate corresponding parts in the different figures of the drawings.

My invention relates particularly to machines for removing the rind from squashes and similar vegetables; and it consists in certain novel features, as hereinafter fully set forth and claimed, the object being to produce a simpler and more effective article of this character than is now in ordinary use.

The nature and operation of the improvement will be readily understood by all conversant with such matters from the following explanation:

In the drawings, A represents the body of the machine, which consists of a frame b supported by legs d, connected by braces f.

Journalled in the bearings g, on the top of the frame b, is a horizontally-arranged shaft h, bearing on its rear end a large gear-wheel i. A horizontal shaft j is journalled in bearings k on the frame b, and disposed on said shaft is a pinion l, which intermeshes with the gear i, a driving-pulley m being secured to the rear end of said shaft. A collar t is secured to the forward end of the shaft h, and equidistant outwardly-curved levers r are pivoted by one end to said collar.

Longitudinally-arranged curved arms p, provided on their outer ends with outwardly-projecting retaining points or studs q, are piv-

oted near their centers to the upper ends of the levers r, respectively. A sleeve v is fitted to slide on the shaft h between the frame b and collar t, and the inner ends of the arms p are pivoted to said sleeve, said arms and their connecting mechanism constituting an adjustable holder D for the squashes. A horizontally-arranged rod w is fitted to slide longitudinally in a bracket x, secured in the frame directly under the shaft h.

To the outer end of the rod w is secured an upwardly-projecting arm y, forked at its upper end to receive the sleeve v, as shown in Fig. 4, which it partially encircles between annular flanges z formed on said sleeve. A bell-crank lever 15 is pivoted to the bracket x, one end of said lever being bifurcated to receive a stud 25 on the rod w, which is fitted to slide between the arms thus formed. The opposite end of the lever 15 is connected by a pivoted rod 35 to an ordinary treadle 45 pivoted in the body A, a coiled spring 55 connecting the bracket 15 with said treadle and acting contractively to keep the same elevated. The pulley m is connected by a belt 65 with a pulley on a main driving-shaft 75 journalled in brackets 85, secured to the ceiling 95 of the room. An ordinary rotary knife H, (see Fig. 5,) which consists of a series of radiating blades 14 bolted to a shaft journalled in a frame 24, is employed for paring the squashes. At each end of the blades is a circular guide 34, for preventing them from cutting too deeply into the body of the article being pared. A grooved pulley 44 is secured on one end of the knife-shaft, and a guard-plate 54 is fastened to the frame 24, said plate being provided with a handle 64, by which the knife is manipulated. Two vertical supporting-rods 74 and 84 are secured to the frame 24 and are connected by a brace 94. Projecting downward from the ceiling 95 is a vertically-adjustable rod 13, (see Fig. 1,) provided on the lower end with a horizontally-arranged block 23. A tube 33 is swiveled by its upper end in the block 23 (see Fig. 6) by means of a ball 43, the supporting-rod 84 of the knife being secured in the lower end of said tube by set-screws 53. A grooved pulley 63 is secured to the end of the driving-shaft 75, and a belt 73, which passes through the guide-block 23, connects said pulley with the

pulley 44 on the knife-shaft. A vertical arm 12 is secured by its lower end in a convenient position on the frame *b*, the upper end of said arm being provided with a hook 22, upon 5 which the knife *H* may be hung when not in use.

In the use of my improvement the squash is first divided in half and a section *K* of it is disposed on the holder *D*. The operator then 10 depresses the treadle, causing the bell-crank lever 15 to throw the rod *w* forward, thereby forcing the sleeve *v* on the shaft *h* in the same direction. This causes the arms *p* to move forward and the levers *r*, pivoted to said arms 15 and to the stationary collar *t*, to be forced outward and spread or separate said arms, thereby forcing the points *q* into the body of the squash and securing it firmly on the holder. Power being applied to the shaft 75, the shaft 20 *j* is set in motion by the belt 65, causing the shaft *h* to revolve and carry with it the squash on the holder *D*, secured on said shaft, as described. At the same time the knife *H* is set in motion by the belt 73, and the operator, 25 grasping the handle 64 on said knife, forces the blades 14 thereof against the surface of the squash, thereby quickly removing the rind, in a manner that will be readily understood by all conversant with such matters 30 without a more explicit description. It will be seen that the swiveled tube 33 permits the operator to readily adjust the knife to the surface of the squash. After the rind is removed the operator releases the treadle 45, when the 35 spring 55 at once causes the bell-crank lever 15 to draw back the rod *w*, and thereby close the arms *p* of the holder and enable the squash to be readily removed.

Having thus explained my invention, what 40 I claim is—

1. The combination of a rotary knife provided with a pulley and a supporting-rod, an adjustable bracket adapted to be secured to the wall of a room, a tube swiveled in said 45 bracket and adapted to receive said supporting-rod, a main driving-shaft bearing a pulley, and a belt connecting the pulleys on said knife and shaft, substantially as described.

2. The combination of the knife *H*, provided 50 with the guard 54 and pulley 44, the supporting-rod 74 and 84, the tube 33, swiveled to a stationary object and adapted to receive the rod 84, and adjunctive mechanism for actuating said knife, substantially as set forth.

55 3. The combination of a body or frame, a rotating shaft journaled in said frame, an expandable holder secured to said shaft and provided with retaining-points, a sliding rod in

said frame bearing an arm in engagement with said holder, a bell-crank lever for actuating said rod, a treadle pivoted in said frame and connected by a rod with said lever, and a spring connecting said treadle and frame, whereby said holder may be opened as the treadle is depressed and closed as said treadle 60 is released, substantially as described.

4. The combination of the body *A*, provided with the shaft *h*, the holder *D*, secured to said shaft and provided with the sliding sleeve *v*, having flanges *z*, the sliding rod *w*, provided 70 with the forked arm *y*, engaging said sleeve between said flanges, the bell-crank lever 15, for actuating said rod, the treadle 45, connected with said lever by the rod 35, and the spring 55, connecting said treadle and body, substantially as and for the purpose set forth.

5. In a machine of the character described, the combination of a body provided with a rotating shaft, an expandable holder disposed on said shaft, treadle mechanism provided with 80 a spring, whereby said holder may be opened as the treadle is depressed and closed as it is released, a rotary knife provided with a pulley and a supporting-rod, a tube swiveled to a stationary object in which said rod is adjustably secured, and adjunctive mechanism for conjointly actuating said shaft and knife, all being arranged to operate substantially as specified.

6. The rotary knife *H*, comprising the frame 90 24, blades 14, and guards 34, secured to a shaft 24 journaled in said frame, the guard 54, and handle 64, in combination with the supporting-rod 74 and 84, the tube 33, adapted to receive the rod 84 and swiveled in the block 95 23, secured to the adjustable bracket 13, and adjunctive mechanism for actuating said knife, substantially as set forth.

7. In a device of the character described, the combination of the body *A*, provided with 100 the shafts *h* *j*, the expandable holder *D*, secured to the shaft *h* and provided with the sleeve *v*, fitted to slide on said shaft, treadle mechanism in said body for moving said sleeve, whereby the holder may be opened 105 and closed, the rotary knife *H*, adjustably secured in the swiveled tube 33, and a main driving-shaft belted to said knife and the shaft *j*, whereby said holder and knife may be rotated conjointly, substantially as and for 110 the purpose specified.
